UNITED STATES PATENT OFFICE.

STACY B. HASELTINE, OF CHICAGO, ILLINOIS, ASSIGNOR TO WILLIAM H. MINER, OF CHAZY, NEW YORK.

KEYLESS YOKE.

1,286,305.

Specification of Letters Patent.

Patented Dec. 3, 1918.

Application filed April 13, 1916. Serial No. 90,838.

To all whom it may concern:

Be it known that I, STACY B. HASELTINE, a citizen of the United States, residing at Chicago, in the county of Cook and State of Illinois, have invented a certain new and useful Improvement in Keyless Yokes, of which the following is a full, clear, concise, and exact description, reference being had to the accompanying drawings, forming a part of this specification.

This invention relates to improvements in keyless yokes.

The object of the invention is to provide a yoke and draw-bar connection which avoids the necessity of coupler keys and which is so arranged that the draw-bar may be disconnected from the yoke without disturbing the gear.

Another object of the invention is to provide a draw-bar and yoke connection so arranged that all the parts are easily accessible from the front end of the yoke.

In the drawing forming a part of this specification, Figure 1 is a side elevation of a draw-bar and yoke showing my improvements in connection therewith. Fig. 2 is a horizontal sectional view taken substantially on the line 2—2 of Fig. 1. Fig. 3 is a bottom plan view of the forward end of the yoke. Fig. 4 is a vertical sectional view taken on the line 4—4 of Fig. 1. Fig. 5 is an end elevation of the yoke. And Figs. 6, 7, and 8 are detail perspectives of the locking block retainer plate, and wear plate

35 respectively.

Referring to said drawing, 10 denotes a standard draw-bar having the usual butt 11 provided with upper shoulder 12 and lower shoulder 13. The yoke A, which is preferably a steel casting, is provided with an upper arm 14, lower arm 15, rear connecting portion 16, and a hollow head 17 at its front end. The hollow head 17 is open at the front and comprises side walls 18—18,

45 upper wall 19, and depending bottom portions 20—20 having a recess or space 21 therebetween. On its inner face, the upper wall 19 is provided with a depending integral shoulder 22, the latter being curved on its rear face as indicated at 23 to engage and coöperate with the shoulder 12 of the draw-bar.

To lock the draw-bar in the yoke, the following means are provided. A locking block B is employed having a transversely

extending shoulder 24 curved on its rear face as indicated at 25, said shoulder 24 co-operating with the shoulder 13 of the draw-bar. At its rear end, the block B is provided with oppositely and laterally extending shoulders 26 and 27 which coöperate with depending lugs or shoulders 28—28 on the under side of the yoke. The block B has a horizontal portion 29 on which a portion of the draw-bar butt is supported, the block B 60 gradually tapering rearwardly from said portion 29 as indicated at 30. A wedge-shaped block or wear plate C is employed having a horizontal top portion 31 and beveled face 32 which coöperates with the corresponding bevel face of the block B. The wear plate C is assembled as clearly shown in Fig. 1, and is prevented from rearward movement by an integral shoulder 33 formed in the yoke. The members B and C are 70 inserted from the under side of the yoke through said recess 21 and to properly hold the same in position, I provide a retaining plate D. The retaining plate D is provided with inwardly extending ribs 34 which operate within corresponding grooves 35 formed on the sides of the yoke head. At its front end, the block D is provided with a hollow extension 36 which is adapted to fit over a depending rib 37 on the block B 80 when the latter is in position. The rib 37 and the walls of said extension 36 are perforated to receive a cotter 38.

To disconnect the yoke and draw-bar, the cotter 38 is first withdrawn after which the plate D is moved forwardly until disengaged from the yoke head. The block B and wear plate C are removed from below and the draw-bar may then be dropped downwardly a sufficient distance to clear 95 the shoulder 22. The draw-bar may then be withdrawn forwardly, as will be understood.

I claim:

1. A yoke having a hooded forward end 100 within which is adapted to be received a draw-bar butt, means for engaging the upper shoulder of a draw-bar butt, and devices for coöperating with the lower shoulder of a draw-bar butt, said devices including a 105 block shouldered at its forward end to engage said lower shoulder, said block being also shouldered at its rear end to engage coöperating shoulders on the yoke and prevent forward movement of said block, and a 110

detachable member for supporting said block in operative position.

2. A yoke provided with a hooded forward end having an opening through the 5 bottom thereof, means on said yoke arranged to engage the upper shoulder of a draw-bar, a shouldered block engageable with the lower shoulder of a draw-bar, said block having a T shaped rear end fitting between 10 a pair of depending lugs provided on the yoke, and means for supporting said block in position.

3. A yoke having a hooded forward end and provided with means for engaging the 15 upper shoulder of a draw-bar, a shouldered block located within the hood and arranged to engage the lower shoulder of a draw-bar, and a retaining plate on the underside of the hood for said block, said plate and hood 20 having coöperable tongues and grooves whereby said plate is slidably engaged with hood.

4. A yoke for railway draft riggings having an integral hood at its forward end, said 25 hood having an upper shoulder curved on its rear face to engage the shoulder of a draw-bar, said hood having a recess in the bottom wall thereof and open to the underside, a shouldered block fitting within said recess, 30 the shoulder thereof being curved on its rear face to coöperate with the shoulder of a draw-bar, said curved shoulders permitting a radial movement of the draw-bar, and a plate detachably and slidably interlocked 35 with the hood for retaining said block in position.

5. A yoke having a hooded forward end, and means for detachably connecting said yoke with a draw-bar, said means including 40 a block having an upwardly extending shoulder at its front end and a T shaped rear end, a wear plate interposed between said block and a draw-bar, and a detachable member for supporting said block in operational position.

6. A yoke having a hooded forward end within which is adapted to be received a draw bar butt, means for engaging the upper shoulder of a draw bar butt, and devices for coöperating with the lower 50

shoulder of a draw bar butt, said devices including a block shouldered at its forward end to engage said lower shoulder, said block being also shouldered at its rear end to engage a coöperating shoulder on the yoke and prevent forward movement of said block, and a detachable member for supporting said block in operative position.

7. A yoke for draft gears, comprising a U-shaped member forming the top and bottom of the yoke, said top being provided with an integral lug to receive the draw bar stresses, a downwardly displaceable member having a corresponding lug, means on said displaceable and bottom members adapted for interlocking engagement to transfer the draw bar stresses to said bottom member, and means for retaining said displaceable member in operative position.

8. A yoke for draft gears, comprising a U-shaped member forming the top and bottom of the yoke, and a hood adapted to surround the butt of the draw bar, a downwardly displaceable member within said hood beneath the draw bar butt and having interlocking engagement with the bottom of said yoke, said top and displaceable member being provided with means to receive pulling stresses from the draw bar, and means for retaining said displaceable member in operative position.

9. A yoke for draft gears, comprising a U-shaped member forming the top and bottom of the yoke, and a hood integral therewith adapted to surround the butt of the draw bar, said top being provided with a lug to receive pulling stresses from the draw bar, a downwardly displaceable member within said hood beneath the draw bar butt and provided with a corresponding lug, lugs on said displaceable member and the bottom of said yoke to provide for interlocking engagement therebetween, and a key to retain said displaceable member in operative position.

In witness that I claim the foregoing I have hereunto subscribed my name this 15th day of March, 1916.

STACY B. HASELTINE.
